UNITED STATES PATENT OFFICE.

ALBERT H. DE VOE, OF WESTFIELD, NEW JERSEY, ASSIGNOR TO THE SINGER MANUFACTURING COMPANY, A CORPORATION OF NEW JERSEY.

FEEDING MECHANISM FOR SEWING-MACHINES.

1,250,437.

Specification of Letters Patent. Patented Dec. 18, 1917.

Application filed March 5, 1915. Serial No. 12,274.

To all whom it may concern:

Be it known that I, ALBERT H. DE VOE, a citizen of the United States, residing at Westfield, in the county of Union and State of New Jersey, have invented certain new and useful Improvements in Feeding Mechanisms for Sewing-Machines, of which the following is a specification, reference being had therein to the accompanying drawings.

10 This invention relates to improvements in feeding mechanism for sewing machines and particularly that class of sewing machines adapted to act upon heavy work such as burlap bags, overalls and the like. In work of 15 this character it has been customary to employ auxiliary feeding means in connection with the main feed device in order to assist the latter in its feeding action, and particularly in work of such nature that the feeding 20 elements must cross lapped or welted seams which tilt the presser member so that only a portion of the gripping face of the feed-dog is effective. By the present improvements a unitary feeding structure is provided which overcomes the necessity for auxiliary feeding means.

In the present construction the improvements comprise a feed-dog having a gripping surface of large area and cooperating 30 with a plurality of presser-members each independently yielding and arranged in such manner that they may be simultaneously raised by means of a single lifting-lever. The forwardly disposed presser-member is 35 arranged with its work-engaging surface mainly behind the needle and is intended to be pressed downwardly by a spring preferably so adjusted as to produce a relatively light pressure upon the work. The rearwardly disposed presser-member is 40 preferably arranged as closely as is practicable to the forward presser-member and is adapted to be pressed downwardly by a spring adjusted to produce a relatively heavy pressure 45 sure thereon to enable the feed-dog to firmly engage and feed the stitched work. The feed-dog is so related to its supporting and actuating members that throughout its feeding action on the work it remains substantially parallel with the throat-plate and in operative relation with each of the presser-

members. The feed-dog is supported at the upper end of a sliding post loosely fitted within apertures formed in the intermediate yoke-shaped portion of a reciprocating feed-bar suspended between two links which connect the arm with supporting shafts, one of the shafts being an actuating rock-shaft to which one link is fixed and hence operative as a crank-member to transmit reciprocating movements to the feed-bar and feeding movements to the feed-dog. The said rock-shaft has a slide-pin and socket connection with an adjustable eccentric on the driving shaft; and a second eccentric on the shaft is 55 connected by similar elements with a feed lifting-lever fulcrumed upon the frame and having a link connection with the sliding post which sustains the feed-dog.

The means for lifting the presser members simultaneously comprise a lifting-lever fulcrumed upon the frame of the machine and connected with a sleeve loosely fitted upon one presser-bar immediately below a collar thereon. An arm projecting from the 75 sleeve immediately below the collar or collars carried by the other bar or bars serves to engage and move the said bars upward when the sleeve is raised; and inasmuch as the said collars are above the acting faces of 80 the sleeve and arm each bar may yield independently of its fellow bar or bars. In the present arrangement the presser-bars are in tandem at the rear of the needle or needles.

In the drawings, Figure 1 is a front elevation of a machine embodying the present improvements and Fig. 2 is a rear perspective of the same, the frame of the machine being indicated by dotted lines in each of said figures. Figs. 3, 4 and 5 are detail perspective views of the feed actuating elements. Fig. 6 is a perspective view of certain elements by means of which the presser-bars are simultaneously raised.

As represented in the drawings, the improvements are shown applied to a sewing machine frame comprising the bed A, standard B and overhanging arm C. Rising from the bed are the bearing supports *a*, *b* and *c*, and secured to the upper faces of the supports *a* and *b*, by means of fastening screws 1, is the throat-plate 2, formed, as usual,

with a serrated upper face and with longitudinal slots to receive the toothed sections of the feed-dog 3.

The feed-dog is secured upon the upper 5 end of a slide-pin 4 loosely fitted within the apertures 5 and 5^x of a feed-bar 6, the lower aperture 5^x being formed in an intermediate underlying arm 6^x of the feed-bar. The feed-bar is provided at its ends with the 10 apertured bosses 7 which are adapted to receive the pins 8 which serve to connect the bar to the sustaining links 10 and 11. The link 10 comprises two spaced sections rigidly connected by a lower apertured boss 12 and 15 an intermediate cross-bar 10^x, the link 10 being pivotally mounted upon a short shaft 13 fitted within suitable apertures formed in the bearing supports *b*, *c*, at the rear of the needles. The link 11 is mounted upon a 20 rock-shaft 14 supported within bearing apertures formed in the supports *a* and *c*, and, as the said link is secured in fixed position upon the rock-shaft by means of a fastening screw 15, it acts as a crank-arm to transmit 25 motion from the shaft to the feed-bar 6 and feed-dog 3.

The feed actuating rock-shaft 14 receives its motion from an adjustable eccentric 16 on the driving shaft 17. The feed actuating eccentric 16 is embraced by a sleeve 18 formed with a boss 18^x apertured to receive the slide-pin 19 held within the aperture 20 of a split-block 21 clamped upon the feed actuating rock-shaft 14 by means of screws 22. 35 By adjusting the eccentric 16 in a manner known in the art a corresponding adjustment may be made in the length of feed.

The feed-lift mechanism comprises a lever 23 formed with the parallel arms *e* and *f* and the apertured yoke *g* embracing the lower end of link 10 and loosely mounted upon the short shaft 13. The lever 23 receives its motion from an eccentric 24 on the driving shaft 17, the eccentric being embraced by the sleeve 25 at the upper end of a short pitman 26 formed with a lower transverse aperture to receive the slide-pin 27 secured in the apertured arm *f* of lever 23 by means of the screws 28. The end of 45 the lever-arm *e* is apertured to receive a stud 29 carried at the lower end of a yoke-link 30 embracing and pivotally connected to a clamping block 31, the pivotal connection being a stud 32. The block 31 is apertured and split to be clamped upon the slide-pin 4 of the feed-dog, a clamp screw 33 serving to secure the block in fixed position upon the said pin. To guide the clamping block 31 in its movements a guide-pin 34 is fitted 50 within suitable apertures formed in the feed-bar 6 and a vertical groove 35 is formed in the clamping block 31 to receive the said guide-pin.

The feed-dog co-operates with the two

presser-feet 36 and 37 pivotally connected 65 to shank-members 36^x and 37^x. The shank-member 37^x of presser-foot 37 is clamped by means of screw 39 upon presser-bar 40, and the shank-member of presser-foot 36 is clamped by means of screw 41 upon the 70 presser-bar 42, the said presser-bars being mounted within suitable bearing apertures formed in the head of the overhanging arm C at the rear of the needle-bar 43. Any suitable spring devices, such as the leaf springs 75 40^a and 42^a may be employed to exert yielding pressure on the presser-bars 40 and 42 and adjusting means, such as the screws 40^b and 42^b, are provided for the purpose of varying the spring pressure on the presser-bars 40 and 42 as may be desirable. The presser-bar 40 is embraced by a sleeve disposed immediately below a collar 45 clamped upon the bar by means of screw 46 and having a lateral extension 45^x slotted to afford a guide for the presser-bar 42. At its lower end the sleeve 44 is provided with a short arm 47 which lies immediately below a block 48 fixed upon presser-bar 42 by means of clamping screw 49. Thus it will be seen that 90 the sleeve 44 in its upward movement will engage the stop members 45 and 48 connected to the presser-bars and will simultaneously raise both of the presser-feet.

In the operation of the improved feeding 95 mechanism the front presser-foot 36, which embraces the needle-path, exerts sufficient pressure on the work to properly compress and hold the same for the stitching operation and, being arranged mainly in rear of 100 the needle-path, does not cause objectionable relative slippage of the layers of material being stitched together. Inasmuch as provision is made for adjusting the springs independently a relatively heavy spring-pressure 105 may be applied to the rear presser-foot 37 so that the feed-dog may firmly grip and feed the material. Relative slippage of the various layers is not to be feared at this point as the work is securely stitched together. Since the presser-feet 36 and 37 are arranged close together undue stretching of 110 the stitched seam is avoided when an obstruction, such as a heavy cross seam, is being drawn under the tip of the front presser-foot and, as a result, the stitches are all of uniform length. The close arrangement of the presser-feet also facilitates turning corners and sewing curved seams of short radius 115 as will be readily understood.

The presser-feet may be simultaneously raised by means of a hand-operated lifting-lever 50 fulcrumed upon the head of the overhanging arm C at 52 and formed with a cam-nose 53 adapted to be thrown into engagement with a roller stud 54 carried by the sleeve 44, the lever being operated in the usual manner. If it is desired, the

presser-feet may be simultaneously raised by means of a treadle-operated lever. This lever 55 is fulcrumed upon the overhanging arm C by means of a stud-screw 56 and at its forward end is apertured to receive a stud 57 projecting from the sleeve 44. In practice, the lever 55 is connected by a chain or rod to a treadle to enable the operator to insert and remove work from the machine without the necessity of employing the hands to manipulate the hand-lever 50.

Having thus set forth the nature of the invention what I claim herein is:—

1. A sewing machine comprising in combination, a frame, stitch-forming mechanism including a reciprocating needle, a plurality of independently yielding presser-bars mounted in said frame, a presser-foot carried by each bar, said presser-feet being arranged one in advance of the other, the forwardly disposed presser-foot being arranged mainly in rear of the needle-path, and feeding mechanism including an elongated feed-dog having a work-engaging portion opposed to and coöperating with said presser-feet throughout its feeding action on the work.

2. A sewing machine comprising in combination, a frame, stitch-forming mechanism including a reciprocating needle, a plurality of independently yielding presser-bars mounted in said frame, a pivotally mounted presser-foot carried by each bar, said presser-feet being arranged one in advance of the other, the forwardly disposed presser-foot being arranged mainly in rear of the needle-path, and feeding mechanism including an elongated feed-dog having a work-engaging portion opposed to and coöperating with said presser-feet throughout its feeding action on the work.

3. A sewing machine comprising in combination, a frame, stitch-forming mechanism including a reciprocating needle, a plurality of independently yielding presser-bars mounted in said frame, a pivotally mounted presser-foot carried by each bar and having a substantially flat work-engaging surface, said presser-feet being arranged one in advance of the other, the forwardly disposed presser-foot being arranged mainly in rear of the needle-path, and feeding mechanism including an elongated feed-dog having a work-engaging portion opposed to and coöperating with said presser-feet throughout its feeding action on the work.

4. A sewing machine comprising in combination, a frame, stitch-forming mechanism including a reciprocating needle, a plurality of spring-pressed presser-bars mounted in said frame, means for adjusting the spring-pressure on at least one of said presser-bars, a presser-foot carried by each bar, said presser-feet being arranged one

in advance of the other, the forwardly disposed presser-foot being arranged mainly in rear of the needle-path, and feeding mechanism including an elongated feed-dog having a work-engaging portion opposed to and coöperating with said presser-feet throughout its feeding action on the work.

5. A sewing machine comprising in combination, a frame, stitch-forming mechanism including a reciprocating needle, a plurality of independently yielding presser-bars mounted in said frame, a presser-foot carried by each bar, said presser-feet being arranged one in advance of the other, the forwardly disposed presser-foot being arranged mainly in rear of the needle-path, and feeding mechanism including an elongated feed-dog having a work-engaging portion opposed to and coöperating with said presser-feet throughout its feeding action on the work, said feeding mechanism also including means for imparting work-advancing movement to said feed-dog while maintaining the latter in substantially parallel planes throughout such movement.

6. Feeding mechanism for sewing machines, comprising in combination, a frame, a driving shaft mounted therein, a feed-bar, a feed-dog having a work-engaging surface, a supporting post therefor mounted for sliding movements in said feed-bar in a direction transversely of said work-engaging surface, means connected to said driving shaft for imparting sliding movements to said post, spaced links carrying said feed-bar and confining it to move in substantially parallel planes, and actuating connections between said shaft and feed-bar.

7. In feeding mechanism for sewing machines, the combination with a frame and a driving shaft mounted in said frame, a feed-dog and a sliding post therefor, a feed-bar formed with an apertured yoke affording spaced guiding members for said post, means for reciprocating said feed-bar, a rock-lever operatively connected with the driving shaft and a link connection between the rock-lever and the sliding post.

8. In feeding mechanism for sewing machines, the combination with a frame and a driving shaft mounted therein, of a feed-dog and a supporting post therefor, a collar clamped upon said post, a feed-bar apertured to receive said post, a rock-lever connected with the driving shaft, a link connecting the rock-lever and said collar, and spaced links between which the feed-bar is suspended, one of said links being operatively connected to the driving shaft to impart reciprocatory movements to the feed-bar.

9. In feeding mechanism for sewing machines, the combination with a frame and a driving shaft mounted therein, of a feed-dog

and a sliding post therefor, an apertured feed-bar adapted to receive said post, means for reciprocating said feed-bar, a feed-lift eccentric on the driving shaft and embraced by an apertured sleeve, a rock-lever having a slide-pin fitted within said sleeve, and a link connecting the rock-lever and the said sliding post.

In testimony whereof, I have signed my name to this specification, in the presence of ¹⁰ two subscribing witnesses.

ALBERT H. DE VOE.
